1

This invention relates to a relay-embodying circuit with one or more highly sensitive or milli-volt type switches for affording a warning or alternatively controlling appropriate apparatus upon a change in ambient temperature at a control zone, and in which devices such as e. g. thermo-couples which are very sensitive to changes in ambient temperature are connected to the electrically energised operating element of the switch, e. g. a coil of a switch constructed after the fashion of a milli-volt meter, is adapted to actuate the switch so as to change from a normal or inoperative position to an operative position so as to bring into circuit relays.

With control circuits embodying a highly sensitive switch, e. g. a switch constructed after the fashion of a milli-volt meter and which is operated by energising the sensitive coil therein, the switch is found to be unreliable in operation. For example, assuming that the moving contact of the switch is displaced by reason of the energy developed at the thermo-couple, the direction of flow of current from the normal source through the hair spring of the switch can be such as to implement the current generated by the thermo-couple, so that the switch might perform satisfactory for one switch stage in the operation. However, on the moving contact of the sensitive switch returning to the normal or resting position due to the reduced output of the thermo-couple, at the moment of contact, the implemented E. M. F. introduced into the switch hair spring circuit is still in the same direction to that generated by the thermo-couple, with the result that at the moment of contact the tendency is for the moving contact to leave the normal or resting contact due to the added E. M. F. induced in the hair spring. Accordingly, one object of the present invention is to provide a circuit which obviates the foregoing disadvantage and ensures a positive holding of the moving contact against both of the co-operating contacts in the proper sequence, whereby the apparatus can be adopted with confidence as to its reliability for producing signals or controlling apparatus under conditions demanding great efficiency, e. g. on aircraft for giving warnings of the outbreak of fire and/or for the remote controlling automatically of suitable apparatus such as e. g. heaters, coolers and fire extinguishers.

Another object of the present invention is to combine with the apparatus a test circuit whereby when the apparatus is used with a plurality of control points, e. g. as with the power units of aircraft, by operation of a signal switch an in-

2

stantaneous indication of the effectiveness of the circuits appropriate to all of the control points is obtained.

Having regard to the foregoing the present invention is characterised broadly in that means is provided whereby when an E. M. F. is developed at the device which is very sensitive to temperature changes, e. g. a thermo-couple, to actuate the switch, upon the moving member of the switch reaching its terminal or contact engaging position there is introduced an implemented E. M. F. which adds effectively to the output of the said very sensitive device, and when the output of the said very sensitive device falls so that it cannot overcome the influence of the means tending to return the contact to its original position when the moving contact reaches the terminal return position, an implemented E. M. F. is introduced in the reverse direction to that generated by the said very sensitive device to still further reduce the resistance to the re-assertion of the aforesaid means which returns the contact to its said original position.

In order that the invention may be clearly understood and readily carried into effect drawings are appended here to illustrating embodiments thereof, and wherein:

Figure 1 is a diagrammatic view showing the invention as adapted for use with a single control source.

Figure 2 is a diagrammatic view showing the invention as adapted for use with a plurality of control sources, and

Figure 3 is a sectional elevation of a suitable form of thermo-couple device for use with the present invention.

Referring to Figure 1 of the drawings the control source C. S. from which a warning or other signal is to be derived is shown as embodying a plurality of thermo-couples arranged in series, that is to say a chain of pairs of thermo-couples 5a, 5b, although of course only one pair of thermo-couples may be employed where a simple single control source is contemplated. By way of example in Figure 1 the chain of thermo-couples illustrated can be assumed as being assembled at various vulnerable points on an aircraft engine. The thermo-couple devices are of identical form throughout, each device having its pair of thermo-couples 5a, 5b both exposed to the influence of normal ambient air conditions but one (5b) being shrouded by shroud 5 and the other (5a) clear of the shroud, or more fully exposed, so that the latter will be affected first by the effect of a very sudden change in temperature, e. g.

due to outbreak of fire. That is to say these thermo-couples are self-compensating at a normal or gradual rise of temperature and consequently under these conditions the output of one thermo-couple 5a cancels out the output of its mate 5b.

In the event of flame, or an abnormal temperature rise, impinging on the exposed thermo-couple 5a, the output of this thermo-couple will exceed that of the other, and the resultant E. M. F. i. e. the amount by which the exposed thermo-couple P. D. exceeds that of the other is applied to the moving coil 7 of a milli-volt switch 1. The switch 1 is of the highly sensitive type, e. g. constructed as shown after the fashion of a moving coil milli-volt meter, in which the moving contact is a needle held in engagement with a fixed contact 3 by a hair spring 4.

The application of the aforesaid low E. M. F. to the moving coil 7 of the switch overcomes the hair spring 4 and moves the needle contact 2 from the contact 3 into engagement with another fixed contact 6, and thereupon there is set into operation relay means which enables a source S, e. g. a 24 volt D. C. supply as used on aircraft, to actuate a warning device, such as the lamp L, or other suitable device which for its operation must consume more energy than is obtainable simply from the thermo-couples of the control source C. S.

The said relay means comprises a double wound relay L⁴ having a winding 8 and an oppositely wound winding 14, the winding 8 being connected by lead 10 to the fixed contact 6 and to the negative or return to source S by lead 11, the positive connection to the winding 8 being via lead 10, contact 6, needle contact 2, resistor R¹ lead 9b closed contacts 19, 20, lead 9c and main lead 9 to the positive of source S via resistor R⁶, this circuit including a pair of contacts 5a which are regularly intermittently opened and closed to introduce a pulsating supply to the needle contact 2. There is only a momentary loading of the needle contact 2 due to the fact that when a warning is to be given (or other apparatus brought into operation) by reason of the very low E. M. F. output from the thermo-couples upon the contact 2 moving over into engagement with contact 6, and the winding 8 being energised from the source S, a pair of holding contacts 12 and 13 associated with this winding are closed to transfer the electrical load from the contacts 2 and 6 to a holding circuit.

The said holding circuit comprises lead 13a from main positive lead 9 via the resistor R⁶ to contact 13, contact 12, lead 12a, winding 8 and return lead 11. The warning lamp L is brought into circuit by reason of the closing of a pair of contacts 21 and 22 operated in unison with contacts 12 and 13, the contact 21 being connected to the lead 9 and the contact 22 being connected by lead 22a to the lamp L and via lead 39 to the return lead 11.

Obviously, in a switch constructed after the manner of a moving coil milli-volt meter as is contemplated in the present invention, the contact pressure is exceedingly light, hence as aforesaid, it is desirable to obtain a very positive engagement of the moving needle 2, with each of the contacts 3 and 6 at the moment of contact, and for this purpose the present invention provides means to implement the electrical energy overcoming the influence of the hair spring 4 at the moment when the contact 6 is engaged, and, in the reverse direction, to reduce the

E. M. F. opposing the influence of the hair spring, so that in effect an assisting E. M. F. is introduced for both moments of contact in the circuit of the moving coil 7 in the correct direction to assist the maintenance of the milli-volt switch contacts until they have fulfilled the function of either operating or releasing the relay L⁴.

The said implementing E. M. F. is obtained from the source S by the introduction of the aforesaid resistor R¹ in the operating circuit which resistor, assuming we are dealing with a 24 volt source S, can have a value of 8 ohms, and can be fixed as shown in Figure 1, or may be variable as shown in Figure 2. The current flow, at the moment of contact, to the resistor R¹ (which is in series parallel with the thermo-couple chain), is split, part of it flowing through the resistor R¹ and part of it through the thermo-couple chain via leads 28b, 28a, to the moving coil 7 of the switch 1 which is already under the influence of the output of the thermo-couple which of course corresponds to the amount which output of 5a exceeds that of its mate 5b. As this implementing E. M. F. is in the correct direction i. e. in a positive direction through the coil 7 to assist the output of the thermo-couples, at the moment of engagement of the moving contact 2 with the fixed contact 6, the output of the thermo-couples and the consequent energy in the moving coil is increased by the amount introduced into the thermo-couple circuit from the normal supply source S. In this connection, it will be seen that the lead 9 from the normal supply source S is taken to one side of the thermo-couple chain, the resistance R¹ being in series with the lead 9 from the normal source and the moving contact, and in parallel with the thermo-couple chain circuit and the coil 7 of the switch, i. e. a series-parallel connection.

It will be seen that the said holding circuit is isolated from the pulsating circuit whereby a constant warning light is given. However, if desired the lamp circuit can be broken intermittently via subsidiary contacts on the pulsating relay.

Connected across the said winding 8 of the double wound relay L⁴ is a resistor R³ adapted to reduce the current flow through the winding 8 in preparation for completing the circuit necessary for the requirements of a subsequent "release" circuit. This said winding 8 of the double wound relay L⁴ is effective for performing both functions of operating the relay and transferring the electrical load from the switch contacts 2 and 6 to the holding circuit aforesaid.

The value of the said resistor R³ in relation to the circuit as a whole is such that only a potential of say six volts is applied to the winding 8 to hold it, the remaining volts said eighteen volts of a twenty four volt supply, being developed across a limiting resistance R⁶ in the main feed 9.

The moving contact 2 is now only held against the contact 6 by the very low E. M. F. from the thermo-couple, but when the thermo-couple output is reduced to the normal state, i. e. the state appropriate to the moving contact 2 of the switch into engagement with the contact 3 aforesaid, as e. g. when the flame previously causing the low E. M. F. output from the thermo-couple being extinguished, taking into consideration the influence of the switch spring 4 the lower contact 3 will be engaged, and this will bring into circuit the other winding 14 of the double

wound relay L^4 . The circuit now is from lead 9 , switch button 18 , lead 17 , winding 14 , contacts 15 and 16 (which could now be closed due to operation of the relay L^4) lead $16a$, contacts 3 and 2 , resistor R^1 (in parallel with coil 7 and the thermo-couple chain) lead $9b$, contacts 19 , 20 , lead $9c$, lead $9x$, pulsing contacts $9a$, lead $9y$, lead $13a$, contacts 13 and 12 , lead $12a$ winding 8 and resistor R^3 in parallel, and from thence to negative via lead 11 . In this connection it should be mentioned that the moving contact 2 of the switch is now at a potential of, taking the aforesaid example of a 24 volt source S , eighteen volts with respect to positive of the source S , and, as the aforesaid holding winding 8 of the double wound relay L^4 has only six volts across it, the eighteen volts supplied in the reverse direction to the other winding 14 of this relay L^4 must cause the relay L^4 to release, the release of the said relay L^4 breaking first the holding contacts 12 and 13 , as well as the lamp contacts 21 and 22 , and in immediate succession thereto the contacts 15 and 16 , thereby causing the eighteen volts to disappear, this resulting in the only electrical energy now flowing in the circuit being that normally generated by the thermo-couple. The contact springs of the double wound relay L^4 are so adjusted as to open contacts 12 , 13 , 21 and 22 momentarily in advance of opening contacts 15 and 16 .

As the operating winding 8 of the double wound relay L^4 is connected to full negative by lead 11 and is energised by a positive applied via the limiting resistor R^6 (which may be of a value of 800 ohms), the moving contact 2 and contact 6 of the switch 1 during the initial operating period, and as that during the other or "release" period, the release winding 14 of the double wound relay L^4 is connected to positive by lead 17 , and the moving contact 2 of the meter switch is now at eighteen volts negative with respect to this positive due to the volts developed across the resistor R^6 by virtue of it being in series with winding 8 and resistor R^3 in parallel, it will be understood that the E. M. F. induced in the aforesaid series parallel circuit is, at the "release" period, in the reverse direction to that obtaining when the moving contact 2 and contact 6 engage.

The means for constantly intermittently making and breaking the circuit to the contact 2 and lead 10 to the relay 8 comprises the pulse circuit containing the relays L^1 , L^2 and L^3 , this pulse circuit interrupting at regular and frequent intervals the operating supply in lead $9x$ via contacts $9a$ to the aforesaid double wound relay L^4 , during operating and release stages to prevent misoperation of the switch due to vibration.

The pulsating relays L^1 , L^2 and L^3 are connected across the twenty four volt D. C. supply via resistors R^4 which can have a value of 2200 ohms each, the current being supplied from the continuous supply side of the lead 9 via a lead $9d$ to coil of relay L^1 via $9e$, resistor R^4 to negative. On the operation of relay L^1 , contacts 11 are closed and the supply goes from $9d$ via contacts 11 , lead $9f$, coil of relay L^3 , resistor R^4 to negative. The operation of relay L^3 opens contacts 13 which removes the short circuit from the coil of L^2 , L^2 operates via lead $9d$ coil of L^2 , lead $9h$ to resistor R^4 . The operation of L^2 closes contacts 12 which places a short circuit across the coil L^1 , which causes L^1 to release, which in turn opens 11 contacts, thereby releasing L^3 to close contacts 13 which short circuits coil L^2 to release it and

open contacts 12 to remove the short circuit from L^1 which then re-operates and the sequence is repeated. By adopting short-circuiting method of releasing the relays a distinctive lag is created due to the comparatively slow collapse of flux in a closed circuit.

The aforesaid test button 18 is for the purpose of obtaining a ready indication that the apparatus is in working order, this test button being provided in association with a relay L^5 , the energising of which relay via lead 17 , button contacts $18a$, $18b$ and lead 31 following depression of the button 18 , opens contacts 19 and 20 and removes a short circuit from a resistance R^2 in series with the thermo-couple and coil 7 circuit. This introduces into the thermo-couple chain an E. M. F. equal to the warning output of the thermocouples because the milli-volt switch side (i. e. point r^2) of the resistor R^2 is connected to the negative supply (lead 11) via lead $11a$ through resistor R^5 which can be of 9100 ohms, and the other end of resistor R^2 is connected via $9x$, contacts $9a$ lead $9y$ resistor R^6 to positive. This introduction of the said E. M. F. in the thermo-couple chain and consequent excitation of coil 7 will cause the contact 2 to engage contact 6 , and as already indicated, this will result in contacts 12 and 13 being closed and the transfer of the load to lead $13a$ and return lead 11 , and the contacts 21 and 22 will connect lead $22a$, lamp L and lead 30 to return 11 .

A multiple-plug connector (plugs 23 and sockets 24) is provided for connecting up the relay apparatus to the warning lamp circuit and the supply source S , and the lamp unit can be plugged in by plug contacts 33 and 34 .

When the apparatus is to be adapted to a plurality of control points, the single warning lamp L and switch 1 will be substituted by a number of lamps and switches 1 and double wound relays L^4 with associated circuits corresponding to the number of control sources. By way of example in Figure 2 four control sources are shown, e. g. two port and two starboard aircraft engines. However, as regards the pulsating circuit, the same number of relays L^1 , L^2 and L^3 will still obtain, and each of these relays will actuate its own pair of contacts $9a$ to cover three of the switch circuits, the fourth switch circuit being satisfied simply by adding to one of the relays, e. g. the relay L^1 in Figure 2, a further pair of contacts $9A$. A further slight modification in this multiple-control source circuit consists in the use of a separate plug-in connection 25 for the control source. Breeze type plugs or sockets 26 are provided for connecting the thermo-couple chains of the two engines on the port side to two of the circuits, and a like arrangement 27 being adopted for the starboard side, so that from each socket or plug two pairs of leads $28a$, $28b$ and $29a$, $29b$ are taken, one lead $28a$, $29a$ of each pair being connected to the associated switch coil 7 and the other lead $28b$, $29b$ to the lead $9x$ communicating with the moving contact via the lead $9c$, contacts 20 , 19 , lead $9b$ and the variable resistor R^1 between which and the point of connection of the latter mentioned lead $9b$ from the thermo-couple is interposed the resistor R^2 having a value of 8 ohms.

It is only necessary to employ one push-button 18 and one relay L^5 for testing all of the switch circuits, the relay L^5 controlling all of the contacts 19 , 20 of the four circuits. By distinctively indexing the warning lamps the operator

will be able to ascertain if any particular circuit is not functioning.

In addition to operating the auxiliary relay L⁵ to introduce the equivalent P. D. into the thermo-couple chain, the test button 18 also removes the supply from the "release" windings 14 of the aforesaid double wound relays L⁴ to obviate their functioning and giving a "false clear" signal due to the engagement of the moving contact 2 and contact 3 of each of the milli-volt switches 1 during the break period of the pulse current introduced as a substitute for thermo-couple output.

The normally broken contacts 15 and 16 of the double wound relay (Figure 1) or relays (Figure 2) obviate any accidental false operation of the double wound relays on their release windings 14 due to the fact that the positive leads 9 to the release windings are arranged in common outboard of the release button.

In order to obtain a highly sensitive and very responsive action at the control source the form of thermo-couple shown in Figure 3 is preferably adopted in the thermo-couple chain. Each thermo-couple comprises two lengths of wire 41 and 42 attached at one end to an insulating base disc 43 and having connected across their other ends at points 44 and 45 a dissimilar wire element 46 to provide two spaced points or zones of generation of low E. M. F. Shrouding this arrangement of wires is a cylindrical metallic sleeve 47 integral with a hollow cylindrical cap 48 accommodating the insulating base disc 43 and a cover disc 49 also of insulating material, a base plate 50 being secured to a flange 51 of the cap 48 by screws 52.

The elements 44, 45 and 46 can be arranged as two chromel-alumel thermo-couples in opposition so that with normal slow temperature variations little voltage output is obtained. With any rapid rise of temperature however, as in the case of a fire, the outer exposed thermo-couple becomes hotter than the inner protected one, and the voltage generated operates the appropriate moving coil relay to give a warning. When this rapid rate of rise ceases the difference in temperature between the inner and outer thermo-couples decreases, and the warning is cancelled.

The cap 48 is slotted or otherwise suitably apertured as at 53 for the free access of ambient air or gas to the assembly of wire elements, the upper point 45 of the thermo-couple device being exposed above or close to the rim of the sleeve 47 but protected from injury by upstanding lugs 54 of such sleeve.

Threaded upon the wire elements 42 and 46 is a disc 55 of insulating material having a clearance from the sleeve 47 forming a screen between the points 44 and 45. Hence, the point 45 is more exposed than the point 44 to the direct influence of flame in the vicinity of the device.

Whilst the slotted cap 48 freely admits ambient air or gas to the interior of the sleeve 47 so that normally the points of the thermo-couple device are exposed to the same temperature condition, such slotted cap will act as a muffle to prevent access of flame through the slot 53, so it is immaterial in which direction the flame plays upon the device in order to ensure that the point 45 will be subjected to the influence of the flame in advance of the point 44 in order to obtain the desired momentary distinctiveness in temperature at the points 44 and 45.

The various relays and switches are mounted in a chassis supported in turn by rubber dampers in a housing or on a base plate so that if the ap-

paratus is subjected to vibration, the vibrations will be damped or absorbed by the rubber dampers.

I claim:

- 5 1. In combination a milli-volt switch with a normal conditions contact, an operative circuit contact and a moving contact, means responsive to sudden temperature change to develop a very low E. M. F. of a few milli-volts and connected to said switch to actuate the moving contact, an electrically operated appliance adapted to be actuated from an operative source of electrical energy having a much greater E. M. F. output than the said means, electrically operated means normally isolated from the switch but adapted to connect said appliance to said source and adapted to be fed from said source, means controlled by the actuation of said switch due to sudden temperature change to effectively connect said electrically operated means momentarily via said switch moving contact to said higher E. M. F. source and thereupon to isolate said moving contact from said higher E. M. F. source, and means to feed from said higher E. M. F. source an implementing E. M. F. to assist in proper operative engagement of the moving contact with the operative circuit when the moving contact is actuated to bring in the operative circuit, and means to feed also from said higher E. M. F. source an implementing E. M. F. to assist in proper engagement of the moving contact with the normal conditions contact when the moving contact is actuated in the direction to engage the normal conditions contact.
- 10 2. Electrically operated apparatus for bringing into operation by reason of a sudden change in temperature at a control source an electrically operated warning device, comprising a thermo-couple for location in said source so as to generate a low E. M. F. output, a switch having a fixed normal conditions contact and a fixed operative circuit contact and also a co-operating moving contact actuated by said low E. M. F. output of the thermo-couple, a relay, means to connect said relay to a normal source of supply of electrical energy via said moving contact and said operative fixed contact so as to energise said relay when the said low E. M. F. is generated to engage the moving contact with the latter fixed contact, a holding circuit connected to said relay and adapted to be fed from the normal source, a warning device or other suitable electrically operated appliance in said holding circuit, means actuated by said relay to bring in said holding circuit and cut out said switch so that the said relay is thereupon energised via the holding circuit, a pulsating circuit fed from said normal source and located in the connection from the normal source to said moving contact and operating independently of the holding circuit, a resistance in series parallel with the circuit of the thermo-couple and switch and located in the connection from said normal source to said moving contact which splits the resultant E. M. F. so that part of the E. M. F. flows through said resistance and part through the moving contact actuating means to implement the E. M. F. operating the moving contact, a supply lead in said holding circuit to said relay and a return lead connecting the said relay to the warning device or other electrically operated appliance, and a further relay adapted to be brought into circuit when the normal conditions contact is engaged by the moving contact and connected to said normal source of E. M. F. supply at a potential with

respect to the other relay which will overcome the energy derived from said latter relay and introduce an assisting E. M. F. into the means operating the moving contact when actuated back into engagement with the normal contact, a test circuit with means to bring it selectively into operation, and a further resistance connected across the thermo-couple circuit and the return to the said normal source of E. M. F. adapted upon bringing in the test circuit to introduce into the thermo-couple circuit an E. M. F. equal to the output of the thermo-couple circuit obtaining when the switch is actuated to bring in the first mentioned relay.

3. In combination a plurality of milli-volt switches, means adapted to be located at a plurality of independent control sources and responsive to sudden temperature change in any one of the control sources to produce a very low E. M. F. of a few milli-volts and connected to said switches to actuate one of the switches upon a sudden temperature rise at one of said control sources, an electrically operated appliance common to all of said switches adapted to be actuated from an operative source of electrical energy common to all of said switches and having a much greater E. M. F. output than the said means, electrically operated means with each switch to connect said appliance to said operative source and adapted to be fed from said operative source, means controlled by the actuation of each switch due to sudden temperature change to effectively connect the associated said electrically operated means momentarily via the associated switch moving contact to said higher E. M. F. source and thereupon to isolate said moving contact from said higher E. M. F. source, and means to feed from said higher E. M. F. source an implementing E. M. F. into the means actuating the switch when the switch is actuated to bring in the said appliance and when it is actuated to cut out the said appliance.

4. In combination with a milli-volt switch, means responsive to sudden temperature change to produce a very low E. M. F. of a few milli-volts and connected to said switch to actuate the switch, an electrically operated appliance adapted to be actuated from an operative source of electrical energy having a much greater E. M. F. output than the said means, a holding circuit for the appliance normally isolated from the operative source of electrical energy and said switch, a double wound relay having one winding controlled by the actuation of said switch due to sudden temperature change to effectively connect said electrically operated appliance to said higher E. M. F. source whilst transferring the load due to said source from said switch to said holding circuit, a pulsating relay regularly interrupting the current supply to the switch, a resistor in parallel with said low E. M. F. producing means connected to the switch and in series with said operative source and the switch to produce splitting of the resultant E. M. F. developed across the said resistor so that part flows through the resistor and part through said low E. M. F. producing means to feed from said higher E. M. F. source an assisting E. M. F. into the switch actuating means when the switch is actuated to bring in the said appliance, a resistor connected across said winding adapted to reduce the current flow through the winding, a release circuit adapted to feed an assisting E. M. F. into the switch when the switch is returned to normal and including the other winding of the said

double wound relay, contacts with said two windings, the contacts of the first mentioned winding being closed to bring in the said holding circuit and the said appliance, the contacts of the winding of the release circuit connecting such winding to the switch and through both of said resistors to the return side of the said higher E. M. F. source, and a resistance in the supply to the first mentioned winding by which the voltage applied to the second mentioned winding is greater than that applied to the first mentioned winding.

5. In combination a milli-volt switch, means responsive to sudden temperature change to produce a very low E. M. F. of a few milli-volts and connected to said switch to actuate the switch, an electrically operated appliance adapted to be actuated from an operative source of electrical energy having a much greater E. M. F. output than the said means, a holding circuit for the appliance normally isolated from the operative source of electrical energy and said switch, a double wound relay controlled via one of its windings by the actuation of said switch due to sudden temperature change to effectively connect said electrically operated appliance to said higher E. M. F. source whilst transferring the load due to said source from said switch to said holding circuit, means to feed from said higher E. M. F. source an assisting E. M. F. into the switch actuating means when the switch is actuated to bring in the said winding of the double wound relay and said appliance, the other winding of the double wound relay operating in opposition to and at a greater voltage than the first mentioned winding so as to take charge when the switch is returned to normal condition, means to feed from said higher E. M. F. source an assisting E. M. F. into the switch actuating means when said second mentioned winding is brought into operation and the switch is actuated to cut out said appliance, and means to regularly interrupt the current supply from said operative E. M. F. source to the said switch and the said load transferring means, a test circuit, a manually controlled switch to bring in said test circuit for testing the appliance actuating circuit, a resistor in series with the means producing the said low E. M. F. but normally short circuited, said test switch removing said short circuit and thereby introducing in the low E. M. F. producing means circuit an E. M. F. equal to its predetermined switch operating output, a lead across said resistor and the first mentioned winding to negative and a relatively much higher resistance in said lead.

55. 6. In a fire warning apparatus the combination of a plurality of milli-volt switches, thermocouples adapted to be located at a plurality of independent possible fire outbreak sources and connected to said switches to actuate one of the switches upon a sudden temperature rise at one of said sources, an electrically operated warning device common to all of said switches adapted to be connected to and actuated from a normal operative source of electrical energy common to all of said switches and having a much greater E. M. F. output than the thermo-couples, a double wound relay and a holding circuit with each switch, said double wound relay being adapted to connect via one of its windings said warning device to said operative source and being adapted to be fed from said operative source, means controlled by the actuation of each switch due to sudden temperature change to effectively connect the said winding of the associated said double wound relay momentarily via the associated

switch moving contact to said higher E. M. F. source and thereupon to isolate said moving contact from said higher E. M. F. source and maintain the said holding circuit in operation means to feed from said higher E. M. F. source an implementing E. M. F. into the means actuating the switch when the switch is actuated to bring in the said warning device, the other winding of the double wound relay being connected to said operative source and the switch so as to receive a greater E. M. F. than the first mentioned winding so as to override the first mentioned winding to break the holding circuit when the switch is returned to normal, and means feeding an assisting E. M. F. into the switch actuating means when the second mentioned winding is brought into circuit.

7. A fire warning apparatus according to claim 6 including an auxiliary thermo-couple set to respond to gradual changes in temperature and in series connection with other thermo-couples which respond only to a sudden rise in temperature.

8. Electrically operated apparatus for bringing into operation in response to a predetermined change in temperature at a remote source a warning device or other electrically operated appliance, comprising an operation initiating circuit, a highly sensitive switch in said circuit and also means adapted to be positioned at said remote source and susceptible to the influence of a predetermined form of change in ambient temperature at said remote source so as to change the electrical characteristics of said initiating circuit to actuate the switch, a main holding circuit adapted to be connected to an available normal source of electrical energy and to be closed via said switch consequent upon a predetermined change in said ambient temperature for maintaining the operation of the warning device or other appliance independently of the operation initiating circuit, means actuated consequent upon closing of said holding circuit to relieve the switch of the electrical load due to the holding circuit and to bring into the main holding circuit the warning device or other appliance, means to introduce an assisting E. M. F. into the switch actuating means to ensure positive actuation of the switch during closing of the holding circuit due to said ambient temperature reaching a predetermined critical measurement, and also means to introduce an assisting E. M. F. into the switch actuating means during release of said holding circuit due to a change from said critical temperature at the said remote source.

9. Apparatus according to claim 8 wherein said switch has a moving contact of very light form and an actuating coil and a hair spring similar to a milli-volt meter, and a "normal conditions" contact and a "holding circuit" contact, the coil being connected to the output of the means adapted to change the characteristics of the operation initiating circuit, and the moving contact being connected to the holding circuit via the hair spring.

10. Apparatus according to claim 8 wherein the switch has two fixed contacts which are engaged alternately by a moving contact of very light form actuated by the low E. M. F. developed due to temperature change at the remote source, said fixed contacts being connected to a double wound relay having two oppositely wound windings, one of these windings operating contacts to bring in the holding circuit and being connected across the fixed contact which brings in the hold-

ing circuit when engaged by the moving contact and a return lead of the normal electrical energy supply source, the moving contact being connected to the positive or supply lead of said normal source, the other winding of the double wound relay acting as a release winding and actuating a pair of contacts via which it is connected at one end to the other or "release" fixed contact of the switch its other end being connected to positive of the normal supply, the contacts of the first mentioned winding breaking in advance of the contacts of the second mentioned winding when the switch is returned to normal, said "release" fixed contact being connected via the moving switch contact via a lead including a resistor in parallel with the switch actuating coil and the thermo-couple or said temperature responsive sensitive means in the said remote source, the release winding upon engagement of the moving contact with the "release" fixed switch contact having a higher voltage applied across it than the other winding so as to override the latter winding to cause the double wound relay to release so that the only electrical energy flowing in the initiating circuit can now be only that due to the thermo-couple of low E. M. F. generating means in the said remote source.

11. Apparatus according to claim 7 wherein the said means which changes the electrical characteristics in the operation initiating circuit develops an E. M. F. of only a few milli-volts to operate the switch is adapted to respond effectively to rise in temperature at the said remote source only when said rise is very sudden.

12. Apparatus according to claim 11 wherein said means comprises a thermo-couple device with two coupled points or zones of generation of low E. M. F. one of which is so shrouded that whilst during gradual ambient temperature changes they respond identically and cancel each other out, there is an advance in the response of the unshrouded point or zone relative to the shrouded one when there is a very pronounced sudden change in the ambient temperature, e. g. upon the outbreak of fire in close proximity to the device, to cause a development of a low E. M. F. sufficient to actuate the switch.

13. In combination a milli-volt switch, comprising two fixed contacts, a very light swinging pointer contact adapted to engage alternately the fixed contacts, a hair spring to actuate said swinging contact in one direction, a moving coil adapted to actuate the swinging contact in the other direction, means responsive to sudden temperature change to produce a very low E. M. F. of a few milli-volts and connected to said coil of the switch to actuate the switch, a holding circuit, an electrically operated appliance in said holding circuit adapted to be actuated from an operative source of electrical energy having a much greater E. M. F. output than the said means, said holding circuit being normally isolated from its operative source of electrical energy and from said switch, means controlled by the actuation of said switch due to very sudden temperature change to close said holding circuit and effectively connect said electrically operated appliance to said higher E. M. F. source whilst transferring the load due to said source from said switch to said holding circuit, means to feed from said higher E. M. F. source an assisting E. M. F. into the said coil of the switch when the swinging contact engages one of said fixed contacts to bring in the said appliance and when it engages the other fixed contact to cut out said appliance, and

means to regularly interrupt the current supply from said operative E. M. F. source to the said switch and the said load transferring means so that the switch contacts are only very momentarily included in the holding circuit.

14. In combination a multi-volt switch, an operation initiating circuit including said switch, means to develop a very low change in E. M. F. of a few milli-volts in said circuit to actuate the switch, said switch embodying two fixed contacts and a very light swinging contact adapted to alternately engage the fixed contacts, a hair spring to actuate said swinging contact in one direction, a moving coil adapted to actuate the swinging contact in the other direction against the influence of said hair spring, electrically operated apparatus, a main circuit to connect said apparatus via said switch to a main source of E. M. F. having a much greater E. M. F. than the E. M. F. feeding the operation initiating circuit, means to introduce an assisting E. M. F. into said operation initiating containing circuit from said main source to assist the said coil at each moment of contact of the switch and comprising the introduction of a resistor across said main circuit and one end of said coil, and means to isolate the switch from the main circuit when the main circuit is closed and to maintain such main circuit closed independently of said switch.

15. In combination a thermo-couple chain including a number of thermo-couple devices each having a pair of thermo-couples both exposed to the influence of normal ambient air conditions but having one more exposed than the other so that it will be affected first by the effect of a very sudden change in ambient temperature, a switch having two fixed contacts (normal and main respectively), a very light moving contact to alternately engage the fixed contacts, a hair spring actuating the moving contact in one direction, a moving coil connected in series with said thermo-couple chain so that it is energised to operate the moving contact in the opposite direction against the influence of said hair spring by the very low E. M. F. developed in the chain due to a sudden rise in temperature, a relay, a main circuit adapted to be connected by said relay via said switch to a main source of E. M. F. when said coil is energised to move the moving contact into engagement with said main contact, means to isolate the switch from the main circuit immediately the said connection to the main source of E. M. F. has been effected by the moving and main contacts and to maintain the main circuit closed, means energised from said main source to implement the E. M. F. obtained from the thermo-couple chain to operate said coil when the main contact is engaged and also subsequently to reduce the influence of the E. M. F. opposing the action of said hair spring when by reason of a drop in the ambient temperature of the previously "sudden temperature change influenced" thermo-couple device the moving contact is returned to the normal contact, and means energised from the said main source due to this latter operation of the switch overriding the aforesaid relay and breaking said main circuit.

16. In combination a thermo-couple chain including a number of thermo-couple devices each having a pair of thermo-couples both exposed to the influence of normal ambient air conditions but having one more exposed than the other so that it will be effected first by the ef-

fect of a very sudden change in ambient temperature, a switch having two fixed contacts (normal and main respectively), a very light moving contact to alternately engage the fixed contacts, a hair spring actuating the moving contact in one direction, a moving coil connected in series with said thermo-couple chain so that it is energised to operate the moving contact in the opposite direction against the influence of said hair spring by the very low E. M. F. developed in the chain due to a sudden rise in temperature, a relay, a main circuit adapted to be connected by said relay via said switch to a main source of E. M. F. when said coil is energised to move the moving contact into engagement with said main contact, means to isolate the switch from the main circuit immediately the said connection to the main source of E. M. F. has been effected by the moving and main contacts and to maintain the main circuit closed, a resistor across said main circuit and one end of said coil and in series parallel connection with said chain, so that at the moment of engagement of the moving contact with said main contact part of the current flow due to the main source flows through the resistor and part through the thermo-couple chain to the moving coil of the switch to introduce an implementing E. M. F. into said coil, and means energised from said main source adapted to override said relay and brought into the main circuit when the moving contact is returned to the normal contact due to a drop in said ambient temperature and to reverse the direction of the said assisting E. M. F. through said series parallel circuit to assist the operation of said spring.

17. Electrically operated apparatus for bringing into operation by reason of a sudden change in temperature at a control source a warning or other electrically actuated device, comprising a very sensitive switch operable by an E. M. F. of a few milli-volts, means responsive to sudden temperature change to produce a very low E. M. F. of a few milli-volts and connected to said switch to actuate the switch, an electrically operated warning or other electrically operated device operated from a source of electrical energy having a much greater E. M. F. output than the said means, a holding circuit for the said device normally inoperative, means controlled by the actuation of said switch due to sudden temperature change to effectively connect said electrically actuated device to said higher E. M. F. source whilst transferring the load due to said means controlled by the actuation of said switch from said switch to said holding circuit, and means to feed from said higher E. M. F. source an assisting E. M. F. into the switch actuating means.

18. Apparatus according to claim 17 wherein the said means responsive to sudden temperature change to produce a very low E. M. F. comprises a thermo-couple device with two coupled points or zones of generation of low E. M. F. one of which is so shrouded that whilst during gradual ambient temperature changes they respond identically and cancel each other out, there is an advance in the response of the unshrouded point or zone relative to the shrouded one when there is a very pronounced sudden change in the ambient temperature, e. g. upon the outbreak of fire in close proximity to the device, to cause a development of a low E. M. F. sufficient to actuate the switch.

19. Apparatus according to claim 17 including

a normally open test circuit with means to close it selectively, and means which, upon closing the test circuit, introduces into the circuit of the said means to produce a very low E. M. F. and the switch an E. M. F. approximately equal to the output of said circuit obtaining when the switch is actuated normally by the very low E. M. F. due to the sudden rise in temperature.

20. Apparatus according to claim 17 including means which returns the said switch to normal circuit broken position when the temperature at the control source returns to below the predetermined operative temperature.

WILLIAM HARRY RUFFLE.
